UNITED STATES PATENT OFFICE.

PAUL A. STOVER, OF RACINE, WISCONSIN, ASSIGNOR TO THE STOVER SIGNAL ENGINEERING COMPANY, OF RACINE, WISCONSIN, A CORPORATION OF DELAWARE.

STOP-SIGNAL LAMP.

Application filed April 7, 1923. Serial No. 630,657.

To all whom it may concern:

Be it known that I, PAUL A. STOVER, a citizen of the United States, residing at Racine, in the county of Racine and State of Wisconsin, have invented certain new and useful Improvements in Stop-Signal Lamps, of which the following is a specification.

My invention relates to improvements in stop signal lamps.

The general object of the invention is to provide a simple, economical construction. Another object is to provide an improved socket for the lamp. An additional object is to provide an improved bracket or adjustable support whereby the lamp may be readily mounted on different parts of the automobile, such as the fender, tail light bracket, spare tire rack, or other support, the bracket permitting the lamp to be arranged horizontally and pointed rearwardly.

In the accompanying drawings I have illustrated one embodiment of the invention, in which—

Figure 1 is a front elevation of the lamp;

Fig. 2 is a sectional elevation thereof;

Fig. 3 is an enlarged front elevation of the lamp supporting plate;

Fig. 4 is a sectional elevation on the line 4—4 of Fig. 3;

Fig. 5 is an elevation of one form of adjustable bracket;

Fig. 6 is a side elevation of part of the same;

Fig. 7 is an elevation of a modified bracket;

Fig. 8 shows how the lamp may be mounted using the small bracket; and

Fig. 9 illustrates one use of the larger bracket.

The lamp comprises a parabolic casing 1, having a lens 2 in the front thereof. Said lens has the word "Stop," or other warning, formed by countersinking the letters below the inside surface thereof as shown in Fig. 2. The casing has an arm or bracket 3 secured thereto, by means of which it may be adjustably mounted, as hereinafter explained.

The incandescent lamp 4 is provided with the usual base 5 having projecting pins 6 forming part of a bayonet lock in connection with the lamp support. Said support 55 is formed of a piece of sheet metal 7 hav-

ing a pair of notches 8 therein, whereby said plate may be snapped into a supporting yoke 9 made of a curved strip of spring metal soldered or welded at 10 to the rear of the housing. The ends of said spring 60 are bent to form spring catches 11, permitting the plate to snap into position by pressing it against said spring catches, and also to be readily withdrawn therefrom by a direct pull.

The plate 7 has a circular flange 12 struck up therefrom about a central opening, said flange having a pair of notches therein which extend radially into the plate, forming recesses 13 which receive the pins 6 on the lamp base. The lamp base is inserted through the central opening and then turned a quarter turn to permit said pins to be snapped into a pair of radial recesses 14 by a resilient contact member 15, which 75 engages the center contact 16, of the lamp, and helps hold said lamp in place. Said recesses 14 are pressed into the rear surface of said plate or lamp support 7. Said pins close one side of the circuit, the other 80 side being closed through said spring contact strip 15. Said contact is mounted on a binding post comprising a screw 17 and nuts 18. Said screw is supported on said plate but held out of contact therewith by 85 means of fibre washers 19, 20, as shown in Fig. 4. Said contact strip has a projecting rib pressed therefrom which fits a corresponding recess in the fibre washer 19, thereby positioning said contact centrally 90 of and behind the opening in plate 7 and also preventing turning thereof with reference to said binding post. A conductor 21 extends from the binding post through an insulating bushing 22 in the side wall of 95 the casing.

The supporting bracket shown in Fig. 5 comprises the arm 3 on the casing and a bracket 23 having openings 24, 25, 26 therein, and having a bent up extension 27 at one end thereof. A bolt 28 passes through openings in the adjacent parts and is provided with a lock washer 29. With this arrangement the bracket may be swung through a considerable angle to permit the lamp to be mounted on any convenient part of the car. It is shown in Fig. 9 mounted above the tail light, the bracket 23 being clamped between the rear of said light and the supporting member to which it is at 105 110

tached. Supporting the lamp in this manner is made possible through the provision of openings 24, 25 and 26 in the bracket 23, openings 24 and 26 receiving the ordinary rearwardly projecting retaining bolts of the tail light and opening 25 accommodating the centrally disposed electrical connector thereof.

5 A short bracket 30, Fig. 7, may be substituted for the larger bracket, in case it is desired to mount the lamp on the fender, as shown in Fig. 8, for example, or on the spare tire rack or other supporting frame.

It will be seen that the outer surface of 15 the lens 2 is molded into prisms forming what is known as a "jewel" surface. I thus provide not only an improved lens construction but one having better photometric value or brilliancy. Said lens is held in place in the end of the casing by means of 20 a split metal ring, as shown in Fig. 2, permitting it to be rotated with reference to said casing. With this arrangement, if it is necessary to mount the bracket 23 in horizontal position, the lens may be rotated so 25 as to bring the word "Stop" in a horizontal position. In other words, a universal adjustment is permitted by the bracket and rotatable lens. If desired, said bracket 23 may 30 be provided with notches 31 and 32, as shown in Fig. 5, whereby said bracket may be broken off at this point and used in lieu of the bracket 30 shown in Fig. 7.

What I claim is—

35 1. An automobile signal lamp comprising an outer casing open at one end, a lens closing said opening, a spring yoke secured

to the other end of said casing within the same, a supporting plate held in position by said spring yoke and a lamp mounted on 40 said supporting plate.

2. A signal lamp comprising an outer casing, a spring yoke secured near the center thereof to the inner end of said reflector, a plate having notches therein engaged by the 45 ends of said yoke, a resilient contact secured to said plate behind an opening therein but insulated therefrom, and an incandescent lamp having a base received within said opening and engaging said contact.

3. An automobile signal lamp comprising a casing, a curved strip of spring metal having its ends bent to form catches and secured at an intermediate point to said casing, a metal plate having notches therein to engage said spring catches and having an opening with a struck-up flange surrounding the same, a pair of radial notches in said flange extending into said plate to receive the radial pins of a lamp base, radial depressions in said plate on the side opposite the said flange to receive said pins upon rotation of said base, a yielding contact member secured at the rear of said plate but insulated therefrom, a bottom contact on 60 said lamp base engaging said resilient contact, a binding post electrically connected to said resilient contact, and a conductor extending therefrom through an opening in 65 said casing.

In testimony whereof, I have subscribed my name.

PAUL A. STOVER.
